CARTRIDGE LINK MANUFACTURE

Alwyn E. Borton, South Orange, N. J., assignor to
Associated Patentees, Inc., Ampere, N. J., a corporation of New Jersey

Application December 18, 1941, Serial No. 423,467

4 Claims. (Cl. 59—8)

The invention here disclosed relates to the manufacture of the links for connecting machine gun cartridges in belt formation and the present invention relates particularly to manufacture of the heavier form of links required for the 20 millimeter and other larger size cartridges.

Special objects of the invention are to accomplish rapid production of the heavier size cartridge links with the least possible waste of material and to accomplish these results with machines available at the present time and which may be readily altered in design to operate for such purposes.

Other desirable objects and the novel features of invention through which all objects are attained, are set forth or will appear in the course of the following specification.

The drawings accompanying and forming part of the specification illustrate certain preferred embodiments of the invention. Structure and operation however, may be modified and changed as regards such disclosure, all within the true intent and broad scope of the invention as hereinafter defined and claimed.

Fig. 1 is a top plan or edge view of the pierced, trimmed and initially preformed strip stock.

Fig. 2 is a similar view, on enlarged scale, of the first blank detached and partly formed as at the first or upper level of the machine.

Fig. 3 is a face view of the strip shown in Fig. 1.

Fig. 4 is a similar, enlarged view of the blank cut from the end of the strip and having the cartridge encircling tongues of the same bent to the proper curvature, as in Fig. 2.

Figs. 5 and 6 are face and edge views respectively showing the link with the curved tongues folded back to the final relation, as effected at the second or lower level of the machine.

Figs. 7 and 8 are broken horizontal cross-sectional views, on the first and second levels, as on substantially the planes of lines 1—1 and 8—8 of Fig. 9.

Fig. 9 is a broken view of mechanism at the final forming station with parts appearing in section as on substantially the plane of line 9—9, of Fig. 10.

Fig. 10 is a partial plan view of those parts of the machine required to produce the results illustrated in Figs. 3, 4 and 5, that is, from the initial punching of the strip to the completed article.

Figs. 11 and 12 are opposed face views of the companion back and front die mechanisms shown in Fig. 10.

Fig. 13 is a broken detail of a modification.

Figs. 3, 4 and 5 illustrate successive stages in the conversion of the strip material 15, to the finished link.

5 At the first station, Fig. 3, one pair of punches 16, 16, partially outline the intermediate loop forming tongue portion 17, and edge flanges 18, of one link blank and a second pair of punches 19, 19, partially outline the end loop forming tongue portions 20, 20, of the next blank and a narrow intermediate tie 21, connecting the two embryonic blanks.

When the strip is advanced to the second station, dies 22, 22, remove unnecessary material 15 from the intermediate loop portion 17, of one blank, trimming away the sides and end of such portion at 23, 24, and the ends of the double loop portions 20, of the next blank at 25, 25, also the shoulders of the double loop portions of the blank in advance, at 26, 26.

At the third operating station, the narrow tie strip 21, between adjoining blanks is severed at both ends by a punch 27, and immediately following such severance, preforming dies arch the intermediate portion of the single loop forming tongue 17, to the proper curvature for the loop at 28, and bend out the flanges 18, to the desired outwardly angled and longitudinally curved configuration.

30 At the final station, Figs. 2 and 4, the single tongue 17, at one side of the link and the double tongues 20, 20 at the opposite side of the detached and partly preformed link are bent to their final radius, connected by an intermediate narrow and relatively flat bridge or body portion 29, this work being performed by upper level preforming tools.

The links, formed to the extent indicated in Figs. 2 and 4, and with the loop portions 17 and 20, 20, curved to the proper radii, then drop to a second level, at the final station, where a forked tool coming from the back bends the bridge portion 29, from the flat to the substantially arched relation shown in Figs. 5 and 6, thus in effect 45 hinging the two sets of curved, shell embracing loops into the final closely connected relation shown.

The operations described can all be performed substantially simultaneously, or as parts of a single cycle, on the "multi-slide" machine of Borton Patent 1,883,513, October 18, 1932.

In my copending application Ser. No. 419,062, filed November 14, 1941, more complete details of that machine as redesigned for operations of this type are disclosed and in the present illus-

tration, only so much of such a machine is shown as necessary to bring out the distinguishing features of the present invention.

In Figs. 10 and 11, the punches 16, 16, and 19, 19, at the first station are shown carried by the back slide 30, and coacting with corresponding dies 31, 31 and 32, 32, on the stationary front block 33, Fig. 12.

Similarly, trimming punches 22, 22, on the second back slide 34, coact with corresponding die members 35, 35, on the second front block or anvil 36, at the second station and the cutting punch 27, and flare preformer 37, on the back slide 38, cooperate with cutoff die 39, and the bending and flaring die 40, on the front block 41, at the third station.

The three slides described may be all timed and operated from cams on the back cam shaft of the machine and the dies at the front may be mounted all on a single head block, in which event, the supports referred to as 33, 36 and 41, would be parts of one and the same block structure.

The stock is shown as confined in a guide passage 42, in the front head or die supporting structure 33, 36, 41, and as yieldingly held at the lower edge, at the piercing and trimming stations by spring pressed plungers 43, 44, 45, Fig. 12 and pressed toward the flare preforming die 40, by spring plungers 46, Fig. 10.

The broken lines at the right hand end of Fig. 3, indicate the position of the two blanks at the end of the strip prior to severance and at a time when the end blank has reached a position in front of the stationary forming post 47. The cutoff punch 27 operates at a time when the end blank is held against the post by the sliding center piece 48, of the front tool 49, which then is yieldingly projected toward the post by spring 50, Figs. 7, 9 and 10. The blank which then remains attached to the strip, at the third or preforming station, is thus free to pull back to the full line position under the foreshortening action of the bending dies without disturbing the blank cut off and left at the forming post.

The curving and double flaring or flanging of the last attached blank at the preforming station, gives the blank sufficient shape to be readily held by the slide 48, set in and forming part of the front tool, it being shaped, as indicated in Fig. 7, to enter between and fit the curved flares or flanges 18, 18, at the upper and lower edges of the loop forming portion 17.

This preliminary bending and flaring of the blank also aids to locate it on the forming post 47, the curved and flanged part fitting the curvature of the first forming portion 51, of the post and thereby enabling the blunt forward end 52, of the central tool member 48, to carry the central portion of the blank into the corresponding recess 53, in the post to form the intermediate flat bridge portion 29 of the link. In this action, the curved side portions 54, 55, respectively confine the preformed single tongues of the link to the first portion 51, and bend the double tongues 20, about the front of the second curved portion 56, of the post. The main side portions 57, of the front tool, continuing the action started by the central part 48, carry the tongues 17 and 20, 20, back around the sides of the formers 51, 56, in time for those portions to be met by and curled around the backs of the formers by the infolding benders 58, and 59, 59. The first of these is a single bender pivoted on the back slide 60, at 61, in position to engage the single loop

member 17, and the others are pivoted on the opposite side of the slide at 62, in position to engage the double loop members 20, 20. These three benders may be in the form of flat plates having leverage portions extended in interleaving relation toward the center of the slide and there provided with rounded projections 63 and 64, 64, respectively for engagement with a closing abutment 65, on the back of the post.

10 The leverage extensions of the benders 58 and 59, are shown as engaged by spring plungers 66, and 67, to hold the same opened to the extent permitted by stationary abutment shoulders 68, when the slide is retracted. Thus the back slide 60, 15 will approach the post with these bending fingers in the open relation and, as engagement is effected with the back of the forming post, will close these fingers to curl the loop forming portions to proper curvature around the back of the 20 forms 51, 56, on the post.

To direct the link, preformed to the extent illustrated in Figs. 2 and 4, that is, with the cartridge encircling tongues 17 and 20, 20, curved to the proper radii but connected by a practically flat bridge in too widely separated relation, from the upper level Fig. 9, down to the lower level, a stationary guide 69, Figs. 8 and 9, is provided below the back tool having a cavity 70, in its front face shaped to slidably receive the inwardly curved end portions of the link tongues 17 and 20, 20. Movement of the link from the upper to the lower level is positively effected by a downwardly acting stripper 71, which operates when the front and back slides are retracted fully clear 35 of the preformed link.

In passing from the upper to the lower level, the intermediate bridge portion 29, then in the substantially flat formation shown in Fig. 2, slides down over the face of a narrow stationary forming post 72, at the front, Fig. 8, rounded to the desired final curvature of the bridge portion 29, shown in Fig. 6.

At this lower level position, the link, confined by guide 69, rests upon a supporting shelf 73, at 45 the base of the guide cavity and while so positioned, the back tool 74, advances through the opening 75, in the back of the guide. This tool is forked to straddle and to conform to the rounded face of the narrow post. The projecting portions 76 and 77, at opposite sides of the fork are positioned to engage the single loop 17, and the double loops 20, 20, respectively, to thereby roll these forward to their final closely spaced relation at the sides of the post, while the cavity 55 of the fork is rounding the bridge 29, over the rounded and more or less bulbous nose portion of the post.

In this final forming operation, the loops are 60 carried forward over the concave side portions 78, 79, of the post, in effect interlocking the link over the post.

To release the link from this momentarily interlocked engagement on the forming post, where the flanges 18 have been carried over the upper and lower edges of the part 80, one side of the post, that is, the part designated 80, Fig. 8, is mounted on and carried by a lower portion of the front slide 49, said part being thin enough to enter between the flanges or flares 18, 18, on the arm 17, and having a narrow concave-sided extension 81, which slides in the cavity 82, in the side of the fixed portion 83, of the post and in back of the rounded forming edge portion. This sliding portion in the side of the forming post 65 reinforces the head of the post while the back

tool is putting the arch in the bridge and it is retracted in advance of the down stroke of the stripper 71, so as to be clear of the flanges or flares 18, 18, on the link loop 17, when the link at the upper level comes down and forces the just completed link off the stationary portion of the post at the lower level. In the action of hinging the preformed loops back into their final, closer relation, the ends of the loops are carried clear of the supporting step 18, Fig. 8.

The invention makes it possible to use the full width of the strip stock and while some scrap is unavoidable, the amount of such scrap may be further reduced by shortening the pitch, as indicated in Fig. 13, that is, by cutting the link blanks closer together, with the flange portions 18, 18, of one blank closely adjoining the ends of the loop portions 20, 20 of the next blank and the end portion of a single loop 17, of the first blank taken out from between the loop portions 20, 20 of the next blank.

Certain advantages are attained in the present invention by "flaring" the blank in a preforming operation, instead of after forming up the loops or ring-like members. The combined bending and flaring effected at the preforming station, gives a desired stiffness to these finished portions of the blank and gives the tools a better hold on the blank at the final forming station.

In addition to saving material, the utilization of the full width of the strip gives the link the benefit of the more or less finished and rounded edges of the strip. While shown extending only slightly over the semi-circle in length, it will be appreciated that the loops may extend the full circle and actually form complete rings. Other changes are possible in the form of the link, the machine and the method, all within the scope of the present invention and the claims are to be construed accordingly and the terms employed are to be considered generally in a descriptive rather than in a limiting sense.

In Fig. 12, there is shown a plunger 84, which can be projected by hand into guide passage 42, to act as a stop for the entering end of the strip, thus to enable the machine to be started with the strip in position where the scrap first produced will be so like that produced while the machine is running, that it will be disposed of in normal fashion and not cause any interference. This strip locating stop may be spring retracted to make sure that it will stand clear of the stock and only come into effect when purposely actuated.

What is claimed is:

1. The method of manufacturing cartridge links from the full width of strip stock, which comprises slotting intermediate portions of the strip to outline along the center of the strip, a single intermediate tongue for one blank and spaced end tongues along the extreme edges of the strip, connected by a bridge portion across the center of the strip for an adjoining blank and a narrow intermediate connecting tie between the end of said single intermediate tongue of one blank and the bridge portion connecting the end tongues of said adjoining blank, trimming excess intervening material between the intermediate tongue outlined for one blank, the end tongues of the adjoining blank and the narrow tie con-

necting the blanks, severing the tie connecting the blanks, bending the tongues of the severed blank to cartridge embracing loop formation, by indenting the bridge portion of the severed blank in one direction and then curling the ends of the tongues around in the same direction.

2. The method of manufacturing cartridge links from the full width of strip stock, which comprises slotting intermediate portions of the strip to outline along the center of the strip, a single intermediate tongue for one blank and spaced end tongues along the extreme edges of the strip, connected by a bridge portion across the center of the strip for an adjoining blank and a narrow intermediate connecting tie between the end of said single intermediate tongue of one blank and the bridge portion connecting the end tongues of said adjoining blank, trimming excess intervening material between the intermediate tongue outlined for one blank, the end tongues of the adjoining blank and the narrow tie connecting the blanks, severing the tie connecting the blanks, bending the tongues of the severed blank to cartridge embracing loop formation and in said slotting operation, defining a flange along one edge of the intermediate tongue and in the course of such operations, flaring such flange outwardly in respect to the loop formed by said tongue.

3. The method of manufacturing cartridge links from the full width of strip stock, which comprises slotting intermediate portions of the strip to outline along the center of the strip, a single intermediate tongue for one blank and spaced end tongues along the extreme edges of the strip, connected by a bridge portion across the center of the strip for an adjoining blank and a narrow intermediate connecting tie between the end of said single intermediate tongue of one blank and the bridge portion connecting the end tongues of said adjoining blank, trimming excess intervening material between the intermediate tongue outlined for one blank, the end tongues of the adjoining blank and the narrow tie connecting the blanks, severing the tie connecting the blanks, bending the tongues of the severed blank to cartridge embracing loop formation and in said slotting operation, defining a flange along one edge of the intermediate tongue and in the course of such operations, flaring such flange outwardly in respect to the loop formed by said tongue.

4. The method of manufacturing cartridge links from the full width of strip stock, which comprises blanking out the central portion of the strip in a single intermediate tongue for one blank, the extreme edge portions of the strip in spaced end tongues of an adjoining blank and a bridge connecting said tongues across the center of the strip and a narrow tie connecting said bridge portion with the end of said intermediate tongue of the adjoining blank, severing said tie to free one blank, preforming the blank left attached to the strip by arching and flaring the same immediately after such severance and completing formation of the severed blank by bending the tongues of the same in cartridge embracing loops and on the radius of the arch and flare imparted thereto in the previous preforming stage.

ALWYN E. BORTON.
